UNITED STATES PATENT OFFICE.

JOHN T. MANNING, OF BROOKLINE, MASSACHUSETTS.

FOLDING UMBRELLA.

1,254,823.

Specification of Letters Patent. Patented Jan. 29, 1918.

Application filed April 16, 1917. Serial No. 162,288.

To all whom it may concern:

Be it known that I, JOHN T. MANNING, a citizen of the United States, residing at Brookline, county of Norfolk, State of Massachusetts, have invented an Improvement in Folding Umbrellas, of which the following description, in connection with the accompanying drawing, is a specification, like characters on the drawing representing like parts.

This invention relates to folding umbrellas of that type in which the umbrella stick is formed of two members having a telescopic relation, the inner member having the handle secured thereto and being jointed so that when the members are telescoped together the joint is exposed to permit the handle to be folded. The object of my present invention is to provide a novel umbrella of this type which is so constructed that when the umbrella is closed the two members of the stick may be unlocked to permit them to be telescoped together by simply pressing on one of the ribs of the umbrella. This end is accomplished by providing one of the ribs of the umbrella with a lock-releasing projection constructed to engage the lock and release the latter when the umbrella is closed.

In order to give an understanding of the invention, I have illustrated in the drawings a selected embodiment thereof which will now be described, after which the novel features will be pointed out in the appended claims.

Figure 1 of the drawings shows an umbrella embodying my invention showing the frame in condition for use;

Fig. 2 is a similar view showing the umbrella frame folded;

Fig. 3 is a longitudinal section through the umbrella stick showing the lock or latch for holding the two members of the stick in their proper relative position and also showing the top spring;

Fig. 4 is a longitudinal section through the umbrella stick showing the lower or thumb spring.

As stated above, the umbrella herein shown is of that type in which the umbrella stick is made in two sections having a telescopic relation. These two sections are indicated at 1 and 2, respectively, 1 being the outer section which is tubular in shape and 2 being the inner section which may be either a rod or a tube. The inner section 2 is provided at

one end with the usual ferrule and at its other end it is jointed, as shown at 4, thereby forming the handle section 5 which is pivotally connected to the body section of 60 the inner member 2. The outer member 1 has secured to one end thereof the usual notched collar 6 to which the ribs 7 are pivotally connected in usual manner. 8 indicates the usual stretchers which are pivoted 65 to the ribs at 9 and are also pivoted to a runner 10 which is slidably mounted on the outer section 1. The inner section 2 is capable of sliding movement longitudinally of the outer section 1, and when the umbrella 70 is in use, the inner and outer members of the umbrella stick are in the position shown in Fig. 1, that is, the ferruled end of the inner member 2 projects beyond one end of the outer member 1 and the joint 4 of the 75 inner member is situated within the outer member at the other end thereof and is thus held rigid. When the umbrella is to be folded, the inner section is moved within the outer section into the position shown 80 in Fig. 2, so that the ferruled end of the inner member is drawn within the corresponding end of the outer member and the joint 4 of the inner member is carried beyond the outer member so that the handle 85 section 5 can be folded. This reduces the length of the umbrella to the length of the ribs.

A latch or lock is provided for locking the two members of the umbrella stick in 90 the position shown in Fig. 1. This lock is shown at 11 and it is carried by a spring arm 12 which is secured to the inner member. The outer member is provided with a locking slot 13 which is so situated that 95 it is in alignment with the lock 11 when the two sections of the umbrella stick are in their operative position shown in Fig. 1. When, therefore, the parts are in this position the resiliency of the spring 12 100 forces the lock or latch 11 through the slot 13 thus locking the two members of the umbrella stick from movement relative to each other.

In order to fold the umbrella, the lock 105 11 is depressed and thus withdrawn from the slot 13. This is herein accomplished by means of a lock-releasing projection 14 carried by one of the ribs 7. When the umbrella is closed, this projection 14 engages 110 the latch 11, as shown in Fig. 1, and by grasping the umbrella at the point where

the projection 14 is located and forcing the ribs inwardly, said projection will depress the latch 11 and thus release it from its locking engagement with the outer member 5. When this has been accomplished, then a pressure applied to the ferruled end of the inner member 2 will force the inner member into the position shown in Fig. 2, thus releasing the joint 4 to permit the 10 handle to be folded. The folding of the umbrella may, therefore, be accomplished by simply closing it and then grasping the umbrella opposite the projection 14 and placing the ferrule of the umbrella against 15 the floor, table or other support, and applying downward pressure to the outer member.

In order to extend the folded umbrella the handle section 5 is swung into alignment with the body portion of the inner member 2 and said inner member is then moved longitudinally of the outer member until the locking latch 11 snaps into the notch or slot 13. When the parts are in this position, the joint 4 will be situated within 20 the end of the tubular outer member 1 and the handle will thus be held rigid. After 25 the inner and outer members are thus locked together, the umbrella can be opened and closed in usual manner by sliding the runner 10 up and down on the outer member 1.

15 indicates the usual top spring which coöperates with the runner to hold the umbrella open and 16 is the usual lower or thumb spring which coöperates with the runner to hold the umbrella closed. The top spring is shown as secured to the inner member 2 and as operating through a slot 30 17 formed in the outer member. The spring

16 is also secured to the inner member 2 and operates in a slot formed in the outer 40 member.

While I have illustrated herein a selected embodiment of my invention, I do not wish to be limited to the constructional features shown. 45

I claim:

1. In an umbrella, the combination with a compound umbrella stick comprising an outer tubular member and an inner jointed member extending through the outer member and slidable longitudinally thereof, of ribs hinged to said outer member, a runner slidable on said outer member and connected to the ribs, a latch for locking the inner and outer members of the stick from relative longitudinal movement, and a projection on one of the ribs adapted to engage the latch and release same when the umbrella is closed. 55

2. In an umbrella, the combination with a compound umbrella stick comprising an outer tubular member and an inner jointed member extending through the outer member and slidable longitudinally thereof, of ribs hinged to the outer member, a runner slidable on the outer member and connected to the ribs, a latch carried by the inner member and adapted to lock the two members together when they are in extended position, and a latch-releasing projection carried by 65 one of the ribs and adapted to engage the latch when the umbrella is closed. 70

In testimony whereof, I have signed my name to this specification.

JOHN T. MANNING.
